his attorney.

UNITED STATES PATENT OFFICE.

HERMAN BURCHESS, OF CHICAGO, ILLINOIS, ASSIGNOR OF ONE-HALF TO ELIAS ROSS,
OF NEW YORK, N. Y.

HINGE.

1,112,888.

Specification of Letters Patent.

Patented Oct. 6, 1914.

Application filed November 3, 1913. Serial No. 798,881.

To all whom it may concern:

Be it known that I, HERMAN BURCHESS, a former subject of the King of Roumania, who have declared my intention of becoming 5 a citizen of the United States, and a resident of the city of Chicago, county of Cook, and State of Illinois, have invented certain new and useful Improvements in Hinges, of which the following is a specification.

10 My invention relates to improvements in hinges and has for its object the production of a hinge, designed for use especially upon suit cases, which will be of durable construction, one which will be so constructed as to 15 be adapted to be securely fastened to the wall of the suit case, or other device in conjunction with which the same is employed, so as to prevent the same becoming readily detached, and one which will be efficient in 20 use.

Other objects will appear hereinafter.

The invention consists in the combinations and arrangements of parts hereinafter described and claimed.

25 The invention will be best understood by reference to the accompanying drawing forming a part of this specification, and in which,

Figure 1 is a transverse section of a suit 30 case equipped with a hinge embodying my invention, Fig. 2 is an enlarged fragmentary section through the hinge portion of the suit case, Fig. 3 is a perspective view of the hinge detached, and Figs. 4 and 5 are perspective views of the component parts of the 35 hinge disconnected.

The preferred form of construction as 40 illustrated in the drawing comprises a leaf 1 provided at one edge with a pintle 2 secured to said leaf by means of ears 3 which project from the terminals of said edge the outer ends of said ears being wrapped around the ends of said pintle.

45 Coöoperating with the leaf 1 is a second leaf 4, formed at one edge with an outwardly looped portion 5, which constitutes a bearing for the pintle 2 which is adapted to snugly engage said portion 5, as clearly shown in Fig. 2.

50 In order to reinforce the bearing loop 5 of the leaf 4, the former is provided with an extension 6 which is adapted, when the hinge is in use, to be securely fastened to

the wall of the suit case, or other device in conjunction with which the hinge is employed, said extension as well as the leaves 55 1 and 4 being perforated to accommodate rivets or other suitable securing devices, whereby the same are securely fastened in position. When the hinge is used in conjunction with a suit case, the leaf 4 is secured to the body 7 of the suit case, the extension 6 being secured to the inwardly inclined flange 8 which is provided at the mouth of a conventional suit case, said extension being inclined slightly to conform 60 with the inclination of the flange to which the same is secured. The leaf 1 is secured to the depending flange of the cover 9 of the suit case in the usual manner, said leaves 1 65 and 4 being interlocked in the manner clearly illustrated in Fig. 2.

Through the provision of the extension 6, it will be seen, that the loop 5 will be materially reinforced or strengthened so as to 70 adapt the same to withstand the severe strains to which the bearing portion 5 is subjected in use, this portion as is known being subjected to severe strains by reason of this portion of the hinge being required to support the weight of the cover when in open 75 position as shown in dotted lines in Fig. 1. By reason of the severe strain to which this leaf of the hinge is subjected when used upon suit cases, the same not infrequently, 80 in a short time, loosens and often is torn from its position. By providing said extension the bearing portion of the leaf of the hinge will be so strengthened and reinforced 85 as to adapt the same to counteract the rough 90 usage and strains to which the same is subjected.

While I have illustrated and described the preferred form of construction for carrying my invention into effect, this is capable 95 of variation and modification without departing from the spirit of the invention. I, therefore, do not wish to be confined to the precise details of construction set forth, but desire to avail myself of such variations and 100 modifications as come within the scope of the appended claim.

Having described my invention what I claim as new and desire to secure by Letters Patent is.

A hinge comprising a leaf having a pin-

tle; a second leaf having an outwardly looped portion at one edge constituting a bearing for said pintle; and a reinforcing extension on said looped portion extending therefrom in a direction opposite to said second mentioned leaf, said extension being formed for fastening in position, substantially as described.

In testimony whereof I have signed my name to this specification in the presence of two subscribing witnesses.

HERMAN BURCHESS.
